INVENTOR

Richard Huitt
BY *F. S. Davenport*

ATTORNEY

UNITED STATES PATENT OFFICE.

RICHARD HUITT, OF KANE, ILLINOIS.

GRAIN-BAG FOLDER.

SPECIFICATION forming part of Letters Patent No. 417,643, dated December 17, 1889.

Application filed July 15, 1889. Serial No. 317,648. (No model.)

To all whom it may concern:

Be it known that I, RICHARD HUITT, of Kane, in the county of Greene and State of Illinois, have invented a new and Improved 5 Grain-Bag Folder; and I do hereby declare that the following is a full and exact description of the same, reference being had to the accompanying drawings, and to the letters of reference marked thereon.

10 My invention relates to a novel machine for folding empty grain sacks or bags, so as to obviate folding by hand, as heretofore, and thus lessen the labor and expedite the operation.

15 My device will be readily understood from the following description of its elements and details and the manner of their combination.

In the accompanying drawings, Figure 1 is a side elevation of my machine. Fig. 2 is a 20 front elevation of the same, and Fig. 3 is a plan view of the folder.

A represents a vertical post or standard mortised into a foot-block *a*, and secured to the floor or otherwise sustained.

25 B represents a bag-rack consisting of a head-piece or cross-bar *C*, the latter journaled horizontally, as shown in Fig. 1, in the upper part of the standard *A*, and projecting sufficiently far through said standard to receive 30 a hand-crank *D*.

To one side of the standard *A* is pivotally secured a catch or stop *e*, adapted to vibrate about its pivot *P*, as indicated by the small arrow, and having in its upper front edge a notch just wide enough to receive the cross-bar or head-piece *C*. This head-piece, it will be observed, is provided 35 with a series of straight horizontally-projecting prongs or bars *r*, preferably round and pointed at their outer or front ends, said

40 prongs and the head-piece in which they are secured forming a revolving rack, which may be retained in the position shown in Figs. 1 and 2 by means of the catch or stop *e*. (See Fig. 1.)

The rack being secured by the catch *e* in 45 the position shown in Fig. 1, the operation of the machine is as follows: The forefinger of each hand is inserted in the mouth of each sack and it is drawn out flat and then slid into one of the spaces between the prongs 50 *r*, always beginning at one side, preferably the right, as shown at *o* in dotted lines, Fig. 2. The space between the prongs being only sufficient to admit the sack when its two sides are brought together, it is prevented from 55 falling through the rack by the thick hem around the mouth. When the rack is filled, the catch *e* is turned back, so as to liberate it. The operator then takes hold of the crank *D*, and by one or two turns folds the sacks 60 smoothly together, after which they are withdrawn from the rack in the direction indicated by the arrow in Fig. 3 and slipped in the usual manner into an empty sack.

I preferably make the rack to contain twelve 65 sacks, so that two fillings and the containing-sack make twenty-five—a quarter of a hundred.

As soon as the rack is emptied it is locked in horizontal position for the reception of another dozen.

Having fully described my invention, what I claim as new, and desire to secure by Letters Patent, is—

In a bag-folder, the parallel prongs *r*, cross-bar or head-piece *C*, post or standard *A*, hand-crank *D*, and catch or stop *e*, all of said parts constructed, combined, and adapted to operate substantially as and for the purpose set forth. 75

In testimony that I claim, the foregoing I have hereunto set my hand this 14th day of May, 1889.

RICHARD HUITT.
